AUTOMOBILE GRILLE

Eugene Bordinat, Jr., Bloomfield Hills, Mich., assignor to Ford Motor Company, Dearborn, Mich., a corporation of Delaware

Filed Nov. 13, 1961, Ser. No. 67,503

Term of patent 7 years

(Cl. D14—18)

FIG. 1 is a perspective view of an automobile grille, showing my new design;

FIG. 2 is a front elevational view of the automobile grille;

FIG. 3 is a top plan view thereof;

FIG. 4 is an enlarged side elevational view thereof;

FIGS. 5, 6 and 7 are enlarged sectional views taken substantially along the lines 5—5; 6—6 and 7—7, respectively, of FIG. 2; and

FIG. 8 is an enlarged fragmentary perspective view taken within the circle 8 in FIG. 2.

It is understood that the fragmentarily shown grille pattern in FIGS. 1 and 4 is continuous as shown in FIG. 2.

I claim:

The ornamental design for an automobile grille, substantially as shown and described.
